DISTINCTIVE PAPER AND METHOD OF
MAKING SAME

Burgess W. Smith, Rochester, N. Y., assignor to
The Todd Company, Inc., Rochester, N. Y., a
corporation of New York

No Drawing. Application April 23, 1934,
Serial No. 721,977

4 Claims. (Cl. 91—67.95)

This invention relates to distinctive paper to be used for making bank notes, checks, labels or other instruments of such a nature that it is desirable to prevent their unauthorized duplication or counterfeiting, and more particularly, to the variety of paper that contains a hidden means of proving its authenticity.

The purpose of the invention is to provide a word or symbol which may be developed at any time to prove the authenticity of the document and further to provide means by which the use of chemicals is avoided, and if so desired, means to cancel the document to prevent the re-use of the paper.

15 To these and other ends, the invention resides in certain combinations and improvements hereinafter more fully described, the novel features being pointed out in the appended claims.

Distinctive papers have heretofore embodied 20 certain features, initially visible, such as planchettes, silk fibres, water-marks, and other similar papers, methods admitting simulation or actual duplication of which are well known in the arts. Another class of distinctive papers contain cer- 25 tain chemicals therein which react to produce a color or other chemical reaction on the application of certain reagents. The determination of the authenticity of such papers requires the pos- session of these chemicals which, at times, is in- 30 convenient and impractical.

By the means of my invention, it is possible to produce a distinctive paper containing a word or symbol that may be developed at any time by the mere application of water which, ordinarily, 35 is always available for the purpose and its duplication requires expensive and ponderous machinery.

I accomplished this invention by the partial or complete destruction of the sizing effect of ordi- 40 nary paper so as to form on the ground of the untreated paper the desired word or symbol, so that when it is immersed or otherwise treated with water, the paper will absorb it into the body of the paper making it more translucent than the 45 area not so treated, thereby making visible the desired insignia.

I accomplished this by immersion of the paper into a solution that will permanently reduce the surface tension of the sizing to the desired extent 50 and cause the solution to penetrate into the body of the paper by pressure of a roll engraved with characters that it is desired to produce which will be invisible when the paper is dry. The apparatus and method of producing visible characters 55 on paper, using a solution of dye, is well known

in the art and is amply described in the patent issued to LaMonte, No. 123,782, dated February 20, 1872, and others.

The solution used for this purpose may be varied to any extent to conform with the nature 5 of the paper, the amount of pressure and the construction of the machine. I find that a mixture of 10% solution of borax and a 5% solution of tribasic sodium phosphate, equal parts of each, is generally satisfactory for this purpose but to 10 secure a more perfect result, I add one quarter of 1% of the sodium salt of the sulphuric acid ester of lauryl alcohol which accelerates and greatly augments the destruction of the sizing where the paper is impressed with the desired characters. 15

The paper, after being impressed with the de- 20 sired characters, may be run through a set of squeeze rolls to remove the surplus solution and dried; or the surplus solution may be removed by immersion in water, the surplus water being 25 squeezed out and the paper then dried; or any variation that may be indicated by the nature of the sizing effect of the paper, the exact details being obvious to those skilled in this art.

After this paper is dried, the sizing effect be- 25 tween the marked and unmarked areas is so dis- turbed and altered that upon the application of water or immersion in that liquid, the characters will absorb more than the ground, making them 30 plainly discernible, although the operation, when 35 skillfully done, does not alter the appearance. After the characters have been developed by such means, the paper may be dried when they will disappear and can be redeveloped at any time by immersion or otherwise applying water in the same manner.

Should this paper be used for the purpose of printing a label, the special features of which are to determine the genuineness of the contents of the package, it is desirable that some means be 40 provided to indicate that it has been developed or has been removed from the original package.

I accomplish this means by printing the label with a water soluble ink so that when the paper is once developed, the visible printing is disturbed 45 so that it no longer retains its original appearance and the areas forming the identifying words or characters will absorb the ink selectively so that the identifying words or characters no longer disappear, an indication that the label has been 50 developed.

To accomplish this effect in a more thorough manner, I may incorporate in the solutions a sub- 55 stance that acts as a mordant for the color that would be used for printing the label or I may coat

the back with interacting chemicals, such as on one side iron salt and on the other a prussiate, which chemicals being separated by an insulating membrane of the paper do not interact until the 5 paper is wet, when they will, and produce a significant color selectively in the letters or design originally produced in the paper by the process outlined.

I am aware that paper has been treated to 10 disturb the sizing effect so as to produce words or designs upon the application of water but I am not aware, before my invention, of the production 15 of words or designs in the manner described. I am not aware of the incorporation of reactive chemicals on opposite sides of a paper when the sizing effect has been disturbed in the manner outlined, or in any other way, so that upon the application of water, the disturbed sizing effect 20 will admit of the production by reason of the combination of said chemicals of a word or design for the purpose outlined.

I do not limit the scope of this invention to the specific materials described or to use water in producing this effect. I may use alcohol or other 25 liquids in combination with paper that has a sizing effect that may be selectively destroyed by the method I have described. The essential feature of this invention is the selective destruction 30 of the sizing effect by causing more of the active material to enter into the paper and destroy the sizing effect wherein impressed while wet with said solution.

It is not essential that the selective destruction 35 of sizing effect in this manner be rendered visible by water. The active bath may be so designed that it will cause the words, characters or designs to appear when moistened with oils or other liquids.

I claim:

40 1. A distinctive paper having hidden words, characters or designs formed by selective variation in the sizing effect, coated on opposite sides with interacting chemicals adapted to develop and render permanently visible said words, characters or designs when said paper is wet with a liquid.

2. The method of producing a distinctive paper which consists in first subjecting a dry sized

paper stock to the action of a colorless liquid capable of modifying the surface sizing of the paper, then impressing said paper stock, while wet with the said liquid, with a member engraved with predetermined indicia to selectively increase the penetration of said liquid and the said modification of the sized surface thereby at the impressed areas to form normally invisible markings, and thereafter drying said paper stock, whereby when paper is moistened said markings 10 are rendered visibly distinct from the unimpressed area.

3. The method of producing a distinctive paper which consists in first subjecting a dry sized paper stock to the action of a colorless liquid 15 capable of modifying the surface sizing of the paper, then impressing said paper stock, while wet with the said liquid, with a member engraved with predetermined indicia to selectively increase the penetration of said liquid and the said modification of the sized surface thereby at the impressed areas to form normally invisible markings, and thereafter drying said paper stock; and printing thereon a visible indicia with a permanent ink adapted to be removed by abrasive treatment of said paper to afford a warning of attempted erasure of any subject matter inscribed on said paper.

4. The method of producing a distinctive paper which consists in first subjecting a dry sized paper stock to the action of a colorless liquid capable of modifying the surface sizing of the paper, then impressing said paper stock, while wet with the said liquid, with a member engraved with predetermined indicia to selectively increase the penetration of said liquid and the said modification of the sized surface thereby at the impressed areas to form normally invisible markings, and thereafter drying said paper stock; and printing thereon a visible design or other subject matter 30 with a sensitive water soluble ink, whereby when said paper is moistened the sensitive ink is absorbed by said modifications in the sized surface of said paper to permanently mark the same and afford a visible warning that said paper has 35 once been developed.

BURGESS W. SMITH.
